UNITED STATES PATENT OFFICE.

HARRY BREGMAN, OF LORAIN, OHIO, ASSIGNOR TO THE STEEL STAMPING COMPANY,
A CORPORATION OF OHIO.

SADIRON HANDLE.

Application filed September 7, 1921. Serial No. 499,087.

To all whom it may concern:

Be it known that I, HARRY BREGMAN, a citizen of the United States, residing at Lorain, in the county of Lorain and State of Ohio, have invented certain new and useful Improvements in Sadiron Handles, of which the following is a specification.

This invention relates to sad-iron handles of the detachable type, and more particularly to the gripping means thereof for holding the handle to the body of the sad-iron.

The main object of the invention is to provide a sad-iron handle of said character, which is easily attached to and detached from the body of a sad-iron and in which the gripping means is of such construction that it will automatically adjust itself to the transverse bar thereof for firmly gripping the same.

A further object of the invention is to provide a sad-iron handle which is of simple construction and stamped from plate material.

With the above and other objects in view, the invention will be hereinafter fully described as illustrated in the accompanying drawings, and the novel features thereof will be distinctly pointed out in the appended claim.

In the drawings similar characters of references are used to indicate corresponding parts.

Figure 1 is a side elevation of a sad-iron with a handle constructed in accordance with the invention attached thereto,

Fig. 2 is a similar view with parts broken away to better show the construction,

Fig. 3 is a bottom plan view of the sad-iron handle,

Fig. 4 is a perspective view illustrating a portion of the gripping lever,

Fig. 5 is a view illustrating the position of the gripping lever when the transverse bar of the sad-iron body is at a right angle to the longitudinal axis thereof, and

Fig. 6 is a similar view illustrating the position of the gripping lever when the transverse bar of the sad-iron body is at an angle with relation to the longitudinal axis thereof.

Referring to the drawings, 1 represents the body of a sad-iron having a central depression 2 and a transverse bar 3, which is ordinary construction. The transverse

bar 3 varies in size and shape in cross section and usually extends straight across with relation to the longitudinal axis of the sad-iron body, but often it extends at a very slight angle relative to said straight across portion due to a defect in casting. This handle has been designed with a gripping means so arranged as to have two gripping edges for firmly engaging said transverse bar, either when straight or on an angle.

The handle is stamped from plate material and consists of a base 4 having turned down flanges 5 and 6, and the free ends of the base extend upwardly at 7 and 8 in any suitable form and are fixed to the ends of a curved hand grasp 9. A downwardly and forwardly extending inclined lug 10 is stamped from the base 4 and is adapted to engage the rear side of the transverse bar 3 of the body of the sad-iron. The base 4 is provided with an opening 11 for receiving a pair of downwardly and forwardly extending hooks 12 and 13 at the rear end of a grip lever 14, and said hooks are adapted to engage the forward edge 15 of said opening for pivoting the grip lever to said base to permit vertical movement thereof. The grip lever 14 is stamped from plate material, and formed at its forward end are a pair of depending lugs 16 and 17 arranged in transverse spaced relation and having teeth at their rear edges for engaging the forward side of the transverse bar 3 of the body of the sad-iron. The lugs 16 and 17 pass thru a recess 18 in the base 4, and this recess and the opening 11 therein are sufficiently wide to allow for a slight lateral movement of said lugs and the hooks 12 and 13 respectively, so that the grip lever 14 may automatically adjust itself and each of said lugs engage the transverse bar 3 whether straight across or on an angle. A finger grip 19 extends from the rear end of the grip lever 14 and is bent over forwardly for lifting the grip lever. A suitable flat spring 20 tends to force the grip lever 14 downwardly and hold it in said position.

In using this sad-iron handle, one or two of the fingers of the hand holding the hand grasp 9 are placed under the finger grip 19 to lift up the grip lever 14, and after applying the base 4 to the top of the body 1 of the sad-iron with the lug 10 against the rear side of the transverse bar 3 thereof, the finger grip is released and its lugs 16 and 17

engage the forward side of said transverse bar due to the action of the spring 20, thereby securely fixing the handle to the body of the sad-iron. Should the transverse bar 3 be on an angle with relation to the longitudinal center of the sad-iron body, or be slightly irregular in form or size as is often the case in castings, the lugs 16 and 17 of the grip lever 14 will automatically adjust 10 themselves to same so that each lug engages the transverse bar and thereby securely holds the handle to the body of the sad-iron. To detach the handle from the body 1, the finger grip 19 is lifted up and the handle 15 lifted from the sad-iron body.

Having fully described my invention, what I claim is:

In a sad-iron, the combination of a body, the body having a depression spanned by a

transverse bar, a handle, the handle having 20 a base, the base having a lug adapted to engage the rear side of said transverse bar, the base being provided with an opening having a forward edge, a lever, the lever having hooks passing through said opening and engaging the forward edge thereof, the base being provided with a recess, the lever having a pair of transversely spaced parallel lugs adapted to pass through said recess for engaging the forward edge of said 30 transverse bar, and said opening and said recess being of sufficient width to allow for lateral and angular movements of said hooks and said lugs to permit adjustment of said lugs to said transverse bar, substantially as described.

In testimony whereof I affix my signature.

HARRY BREGMAN.
